Attorney

UNITED STATES PATENT OFFICE.

MAXEY JACKSON, OF PORTLAND, OREGON, ASSIGNOR, BY MESNE ASSIGNMENTS, TO
MOTOR SAFETY INDICATOR, INC., A CORPORATION OF WASHINGTON.

SPEED-INDICATING SIGNAL.

Application filed April 10, 1922. Serial No. 551,302.

To all whom it may concern:

Be it known that I, MAXEY JACKSON, a citizen of the United States, residing at Portland, in the county of Multnomah and 5 State of Oregon, have invented certain new and useful Improvements in Speed-Indicating Signals, of which the following is a specification.

This invention relates to certain new and 10 useful improvements in speed indicating signals, of that general type in which a light is employed to indicate the speed at which the vehicle is traveling.

My present improvements pertain more 15 particularly to the speedometer, the invention being in the nature of either an attachment to speedometers now in use and well known, or it may be embodied in a speedometer and made a part thereof. In the 20 former instance, the improvement can be readily applied to the speedometers of known construction, such, for instance, as the Stewart speedometer, without any change in the construction of the latter.

25 The present invention has for its objects among others to provide a simple and efficient device readily applied to a vehicle, in any desired position, in any convenient manner. It is designed to indicate by 30 showing any one of a variety of colors of lights the rate of speed at which the vehicle is traveling. The showing of the different colored lights is accomplished in a simple manner and is controlled by the 35 speed of the vehicle so that there can be no error as to the speed indicated by my improvement. It requires no attention on the part of the driver, nor can the driver so manipulate it as to indicate a speed other 40 than at which the vehicle is moving. There is no opportunity for dispute as to the speed and the police or others can readily determine at a distance the rate at which the vehicle is approaching or moving in the other 45 direction.

It use will effect a great saving of life and will aid the police in positively determining the rate of speed at which the vehicle is traveling, for whichever light is 50 exhibited is a positive and indisputable evidence of the speed the car is making.

Other objects and advantages of the invention will hereinafter appear, and the novel features thereof will be specifically 55 defined by the appended claims.

The invention, in its preferred form, is clearly illustrated in the accompanying drawings, which, with the numerals of reference marked thereon, form a part of this specification, and in which— 60

Figure 1 is a rear view with the rear side of the casing removed.

Figure 2 is a top plan of Figure 1, the top of the casing being removed in both views.

Figure 3 is a vertical section as on the 65 line 3—3 of Figure 2.

Figure 4 is a cross section as on the line 4—4 of Figure 3.

Like numerals of reference indicate like parts throughout the several views. 70

In Figure 1, 9 indicates the revoluble member carrying the numerals as usual to designate the speed of the car. This is operated in the usual way and with this part of the device my invention while cooperative does not pertain, except as will now be described. In manufacturing the speedometer anew I would extend this revoluble member to the desired height so that it would be in all respects the same as will 75 now be described in connection with my improvements applied as an attachment to speedometers already manufactured or in use, the two members 9 and 10 being integral. 80

10 is a cylindrical member of any suitable material, such as aluminum, isinglass or whatever may be found most desirable. In applying my improvement as an addition to the known speedometers, I attach this 90 member so as to vertically extend the height of the member 9 and for this purpose I may employ any expedient; the member 10 may be soldered or similarly affixed to the upper end of the member 9, being slipped over the upper edge thereof for a suitable distance for this purpose, as seen in Figure 3, or it may be secured to the member 9 by rivets or the like, as seen at 11 in Figure 1. 95

The member 10 is provided with a multiplicity of openings 12 in which are arranged differently colored glasses 13, to denote the speed at which the vehicle is traveling. For instance, the first glass, that is the one shown when the vehicle is making say five miles, will be white, the next, indicating ten miles also white; the next may be yellow; the next green, the next blue, the next pink, and the next red, or any other arrangement of colors may be employed, 105 110

those denoting the higher speed, however, being red, the color generally employed to denote danger. This member 10 being mounted to revolve with the member 9 of the speedometer, with which it is associated, will, of course, display the color as predetermined to correspond with the speed attained. Thus moving at a slow rate of speed, the white will show, when greater speed is attained the yellow will show; greater speed will cause the green light to be shown, and so on. These colors will be known to the police and others with their corresponding speeds so that it will be readily understood that the speed of the car is automatically indicated.

14 is a plate serving as a support for the upper end of the pivot 15 on which the member 9 revolves. I support or suspend this plate within the member 10 by means of the rods 16, the lower ends of which are screwed into the said plate and their upper ends supported in the plate 17, which latter is supported out of contact with the upper edge of the member 10 so as to avoid friction. This upper plate 17 is supported by means of the rods 18 passed through the said plate and screwed into some relatively fixed part of the speedometer frame, as seen clearly in Figure 1.

The casing may be made of detachably attached parts or otherwise, as may be found most expedient.

20 is an electric light socket adapted for cooperation with an electric lamp 21, as seen in Figure 3. The plate 17 is a skeleton plate for the reception of this socket, as seen clearly in Figures 2 and 3. The wiring for the lamp is not shown; it may be of usual form and disposed within the casing, out of the way. For holding this socket in place, I have shown a spring clamp 22, the cross member of which is secured to the front plate or wall 1 of the casing, as seen at 23, the clamp being formed with the bent portions 24 to embrace the upper ends of the rods 18, as seen best in Figure 2, the free ends of the wire or material of which the clamp is formed being curved, as seen at 25, to snugly engage the socket, as seen in Figure 2, the terminals 26 affording ready means for relieving the socket of the pressure of the clamp when it is desired to remove the socket.

55 The casing may be of any desired shape and size as well as of material.

The operation will be readily understood from the foregoing description and a detailed explanation thereof does not seem

necessary. The device requires no attention on the part of any one; if the car is moving the speed is automatically indicated. At night the lamp being at all times lighted, the color corresponding to the speed of the car is made visible through the front lens 5.

From the foregoing, it will be evident that I have devised a simple, yet efficient and dependable automatic means for indicating the speed at which the vehicle is traveling, and while the structural embodiment of the invention as hereinbefore described is what I at the present time consider preferable, it will be readily understood that the same is subject to changes, variations and modifications in detail, proportions of parts, etc., and I, therefore, do not intend to restrict myself to the construction shown but reserve the right to make such changes, variations and modifications as come properly within the scope of the appended claims. For instance, the revoluble member may be actuated otherwise, the present invention being in no wise restricted to the manner of connection with the wheel or axle.

What is claimed as new is:—

1. In a speed indicator, a revoluble pivoted member of a speed indicating device, a member substantially cylindrical and revoluble therewith, and having differently colored transparent means carried thereby and placed in openings therein, a plate suspended within said last named member and forming a support for the pivot of the first-named member, the two members being revoluble as one, suspending means for said plate, a lamp socket for holding an electric bulb within said cylindrical member, and means for engaging the socket.

2. In a speed indicator, a revoluble pivoted member of a speed indicating device, a member substantially cylindrical and revoluble therewith, and having differently colored transparent means carried thereby and placed in openings therein, a plate suspended within said member and forming a support for the pivot of the first-named member, the two members being revoluble as one, a second plate from which the said first plate is suspended, means for supporting the upper plate, and spring means resting on said upper plate for engaging and supporting a lamp socket for a bulb within the cylindrical member.

In testimony whereof I affix my signature.

MAXEY JACKSON.
